UNITED STATES PATENT OFFICE.

ERNEST E. KOKEN, OF ST. LOUIS, MISSOURI.

RECLINING MECHANISM FOR BARBERS' CHAIRS.

No. 911,135.

Specification of Letters Patent.

Patented Feb. 2, 1909.

Application filed July 25, 1907. Serial No. 385,551.

To all whom it may concern:

Be it known that I, ERNEST E. KOKEN, a citizen of the United States, residing at the city of St. Louis and State of Missouri, have 5 invented certain new and useful Improvements in Reclining Mechanisms for Barbers' Chairs, of which the following is a specification, reference being had therein to the accompanying drawings.

10 This invention relates to barbers' chairs, and particularly to the intermediate connecting means between the back of the chair and the apron which carries the foot-rest.

In the drawings forming part of this specification, in which like numbers of reference denote like parts wherever they occur, Figure 1 is a view of a barber's chair, in side elevation from the base to the enlarged head of the piston and flange supported thereby, and 15 in section above that point, showing said new connecting means in its position relative to the other parts of the chair; Fig. 2 is a sectional view through the piston-head, illustrating the location and arrangement of a 20 means for locking the connected back of the chair and apron in any desired position; Fig. 25 3 is a side elevation, partly in section, of the lever for controlling the vertical adjustment and rotation of the chair body; Fig. 4 is a 30 top plan view of the means intermediately connecting the back of the chair and the apron, showing same with the parts in position for the occupant to recline; Fig. 5 is a 35 perspective view of the chair with the upholstered seat removed, but shown in dotted lines, so as to show the frame for supporting same, and means connecting the frame with the apron; Fig. 6 is a detail, partly in top 40 plan view and partly in section, showing the means of attachment of the apron and chair-back, etc., to the side frames; Figs. 7 and 8 are sectional views of the same details; Fig. 9 is a top plan detail view of the rear rail and 45 connections for same with the side members, and, also, of the transverse member and its mode of connection with the side members; and Fig. 10 is a sectional view on the line 50 10—10, Fig. 9.

The main elements of the mechanism 55 shown in the drawings and their manner of operation have been fully described in my application for patent therefor, Serial No. 157,032, which is still pending. The popu-

larity of the chair therein illustrated, described, and claimed has led to the production 55 of the improvements for which a patent is sought by the present application.

In order that these improvements and their functions may be understood and distinguished from that which is already disclosed by the pending application, the main mechanism will first be redescribed, and afterward said features of improvement will be clearly set forth and, particularly, pointed out in the claims.

Referring to the drawings, 1 is the base of the chair, 2 the pedestal which is in the form of a cylinder, in which the piston 3 reciprocates, said piston being enlarged at its upper end into the casing 4, through which the 70 shaft 5 enters. The chair-back 6 has projections or cheeks 7 adjacent its lower portion, same being pivotally connected at 8 to the side-members or arms 9 of the chair. Located at such a point in the projections 7 as 75 to give them the operative effect of levers, are the pivotal connections 10 between the projections 7, carried by the chair-back 6 and the upward projections 11 from the seat-support 12. This seat-support 12 may be arranged to comprise a pair of side-bars 13, connected by cross-bars 14, thus forming a 80 frame. The seat-support has at its rear end the upward projections 11, and at its forward end the upward projections 15. The side-bars 13 are in the form of angle-irons, having the horizontal flanges 16 arranged angularly 85 with relation to the upright portion 17 of the side-bars 13. Depressions 18 are formed in the flanges 16 of the two side-bars 13 to receive the ends of the cross-bars 14, so that 90 they are countersunk therein and rest upon the plates 19, which are formed integral with the flanges 16 and underlie the depressions 18. Said ends of the cross-bars 14 are 95 pierced by openings through which, at one end, the pins or lugs 20 pass, said lugs being formed integral with the plates 19, and being retained in position by the cotters or split-pins 21 passing through the lugs 20. At 100 their other end, the cross-bars 14 are fixed to the other flange 16 by the bolts 22 or other suitable means.

The side-members 9 may be connected to the piston 3 by any suitable means, so as to 105 move vertically and rotatably therewith, and

are preferably rigidly connected together as, for instance, by the transverse body-supporting portion 23, which is supported by the piston 3, being shown in the drawings as 5 borne by a flange 24 integral with the casing 4 formed on said piston, and adapted to move vertically with said piston, and carrying with it the superstructure of the chair, as hereinafter described.

10 The upholstered seat 25 rests upon the flanges 16, and is held from horizontal movement by the pins or lugs 20 borne by the plates 19, which pins fit into suitable sockets (not shown) in the frame-work of the up- 15 holstered seat 25, the construction of the up-holstered seat being of the common character.

The projections 15 are pivotally connected at 26 to the levers of the third order 27. 20 These levers are fulcrumed at the pivotal points 28, and, by said pivots 28, are connected with the side-members 9. The levers 27 form the supports for the apron 29, which carries the foot-rest 30. The seat-support 25 12 being pivotally connected at 26 to the levers carrying the apron 29, and at 10 to the chair-back 6, and the back 6 being pivoted at 8 to the side-members 9, and the levers 27 being, also, pivoted thereto at 28, and the 30 seat 25 resting on the seat-support 12, it is obvious that the parts that carry the occupant of the chair depend from the pivots 28 and 8, and are adapted easily to swing thereon when motion is imparted to the back 6 by the 35 barber, the side-members 9 being meanwhile stationary.

When the chair is in the reclined position shown in Fig. 4, the foot-rest lock-bar 33 is tightly held by the clamping pieces 34 and 40 35, which normally lock said lock-bar 33 by reason of the pressure of the springs 36 against the plate 34, which tends to press the plate 34 against the bar 33, and the latter against the plate 35, the lock-bar 33 being 45 thus locked. The plates 34 and 35 are pivotally united to each other by the hinge 37. The elongated screw-bolts 38, also, connect them.

When it is desired to place the back and 50 foot-rest in the position for the occupant of the chair to recline, the operator releases the lock-bar 33 by rotating the shaft 5 with the hand-lever 39, and, grasping the chair-back 6 firmly in his hand, pulls same backwardly 55 and depresses same to the desired angle. As the chair-back is pivoted at 8 to the side-members or arms 9 of the chair, it will thus swing downwardly, and, being pivotally connected at 10 to the projections 11 of the 60 seat-support 12, it forces said seat-support 12 in a forward substantially horizontal line the real character of that line being, however, a slight and peculiar but indescribable curve or series of curves, by reason of the fact that 65 it is stationarily pivoted at 8 and again piv-

otally connected at 10 at such a distance from its axis of rotation on the pivotal-point 8 as to cause the lever 7 to impart to it a substantially horizontal longitudinal forward movement. This horizontal longitudinal 70 forward movement of the seat-support 12 causes the projections 15 to push the levers 27, which connect the apron 29 and foot-rest 30 to the seat-support 12, and in this way to raise the same on the pivotal 75 point or fulcrum 28. When the desired movement has been accomplished and the chair reclined at the angle sought, the foot-rest lock grasps the lock-bar 33 and all of the parts connected with the reclining mechanism are immediately locked in the position above stated. When it is desired to return the chair back to the upright position, the lock-bar 33 is unlocked, the barber with his free hand raises the chair-back 6 to a 80 vertical position, which causes all the parts to move in the reverse manner to that above described, and returns same to the position illustrated in Fig. 1.

It is, furthermore, clear that in view of 90 the manner of manipulation of the reclining mechanism exhibited in the present application, as well as of the well-known heavy construction of barbers' chairs, it is essential that a barber's chair shall be provided 95 with a weighty base. This weight is conveniently provided in the chair illustrated in the drawings of the present case in means for the vertical adjustment of the chair which is hereinabove described as a necessity in a barber's chair. Thus, in a barber's 100 chair the weighty base allows for the vertical adjustment of the chair-body, the chair-body is solid and substantial, and the reclining mechanism, which is particularly 105 the object of the present application, is connected with said solid and substantial chair-body, forming part thereof, and the whole unites in a perfect and true combination to form a chair suitable for the purposes of a 110 barber and specially adapted to his exigencies, and hereinafter referred to in the claims as "a chair of the type described".

In the claims the word "base" refers not only to the base proper 1, but to all that base 115 portion of the chair, which includes the pedestal 2 also, as distinguished from the chair-superstructure, which comprises the side-members, the chair-back, the apron, and the part connecting the side-members 120 from which the piston depends.

Having thus explained the chair in which the special improvements which are the subject of the present application are to be embodied, it should next be remarked that 125 it is the purview of the present application that the chair of said pending application shall be constructed of metal instead of wood. While said pending application is not limited to a chair made of wood, yet the 130

drawings thereof exhibit large parts of it constructed of wood, and in said application the details of adaptation of the subject-matter of that application to a metal construction were not worked out because the actual construction of a metal chair had not then been attempted, but same has since been accomplished, revealing the existence of problems requiring the making of the inventions of the present application in order to solve them and to overcome the difficulties arising from the making of said chair chiefly of metal.

With the apron 29 constructed of metal, as in the chair of the present application, it was found that the balance of weight of the chair-back, longitudinally-moving seat-support, the chair-occupant, and the apron was disturbed, due to the greater weight thereby imparted to the apron.

One of the special merits of the construction embodied in the former application is that the parts are so arranged and the seat-support so hung from the moving chair-back and apron as to locate the weight of the chair-occupant in such position and relation to the other members as to derive help, rather than hindrance, from the presence of the weight of the chair-occupant. With the making of the apron 29 of metal, however, it was found that the greater weight thus given to the apron deprived the operator from the chair-back of the advantage of the weight of the chair-occupant resting upon the middle member and being hung from the chair-back and apron, due to the fact that the weight of the apron when made of metal is relatively excessive.

To overcome the disproportion of weight occasioned by the introduction of the metal apron, the relation of the points of pivoting of the apron to the side-members 9 and of the seat-support to the apron, and, again, of the chair-back to the side-members and to the seat-support, must be changed so that the center of gravity of the entire construction, including the chair-occupant, will be altered. This is best accomplished as follows (it being understood in the following description that the movable parts are in the position depicted in Fig. 1).

First, there are provided the elongated arms 31 and 32 projecting rearwardly from the arms or levers 27. The pivotal point for each of said levers 27, by which same are attached to the side-members 9, is located as far forward as possible, while the pivotal points by which said levers 27 are connected to the upward projections 15 from the seat-support are located as far back as possible, the degree of rearwardness of said pivoting being enhanced by the special elongation of the arms 31 and 32. The elongated arms 31 and 32 are substantially at right angles to

the main body of the levers 27. The pivotal points between the projections 15 and the ends of the elongated arms 31 and 32 are so located as to be further toward the rear than in the above-named pending application for patent.

Second, to assist in carrying out the solution of the problems arising from the heaviness of the apron caused by its metal construction, the pivotal points 10 have been moved still further back than in said pending application so as to assist in the rebalancing of the parts. This helps to change the center of gravity of the four members involved in this problem, namely, the chair-back, seat-support, apron, and chair-occupant. By this rearrangement of the relative position of the pivotal points 8 and 10, cooperation is secured between the movement of the chair-back and the levers 27 in a manner which is necessary for the right operation of levers shaped like levers 27, but which was not necessary with the straight levers of the pending application for patent.

Since in the present construction the side-members 9 are formed of metal, it becomes necessary to provide special pivot sockets by which the chair-back and levers 27 may be connected thereto. Moreover, to save unnecessary weight of the structure and to enhance the beauty of the appearance of the chair, the side-members 9 are made of concaved metal, with their convexity outward. This produces in their upper inner portions the effect of a groove 40, and in this groove or concavity 40 are provided the forward bosses 41 and the rear bosses 42. One boss 41 and one boss 42 is formed in a concave portion 40 of each side-member 9, and in the center of each of said bosses is formed a hollow portion or cavity as a socket 43 for the reception of the pintles 44 projecting from the levers 27 and cheeks 7.

The upward projections 15 and 11 are bifurcated in the upper portion thereof so as to form a yoke 45, both arms of which are perforated to receive the pin 46 which passes through said arms and pivots within and to each forward yoke the arms 31 and 32 of the lever 27 and within and to each rearward yoke one of the cheeks 7 projecting from the chair-back.

In the rear of the side-members 9 bosses 47 are formed, which project out of the concavity of the side-members at such a point near the rear wall thereof as to form a seat 48 between same and said rear wall for the end 49 of the rear rail 23^a. As shown in the drawings, the curvature of the rail fits the curvature of the rear wall of the concavity of the side-members. The perforated lugs 50 project forward from the rail 23^a and overlap the bosses 47, so that the bolts 51, passing through the perforations in lugs 50 and coöp-

erating with threads in recesses in bosses 47, firmly bind the rail 23^a to both side-members and thus the latter to each other.

The transverse member 23 is connected to 5 the side-members, and the same thereby to each other, as follows: Lugs 52 project inwardly from the side-members 9. Vertical perforations 53 pass therethrough and register with perforations 54 through the arms 55 10 of the transverse member 23. Bolts 56, passing through the perforations 53 and 54, firmly attach the transverse member 23 to the side-members 9, and, thereby, the latter to each other.

15 A strong unitary structure is formed of the pair of side-members 9, the transverse member 23, and the rear rail 23^a by means of the particular means of attachment of said several parts shown and described, and a structure is thereby provided adapted to receive 20 and be combined with the moving chair-back, apron, connected seat-support, the hanging of which upon connections to such a unitary structure is the dominant feature of this type 25 of chairs.

Having thus described my said invention, what I claim and desire to secure by Letters-Patent is:

1. In a barber's chair, the combination of 30 a chair-body comprising a pair of side-members and a transverse member connecting same, a chair-back pivoted to each of said side-members, an apron also pivoted to each of said side-members, a longitudinally-movable 35 seat-support intermediate said chair-back and said apron and pivoted to both, the pivotal points for the connection of said support to said chair-back being when the chair-back is vertical, to the rear of the pivotal 40 connection of said chair-back to each of said side-members, and the pivotal points between said seat-support and said apron being well to the rear of the points of pivotal connection of said apron to said side-members.

2. In a barber's chair, the combination of 50 a chair-body comprising a pair of side members and a transverse member connecting same, a chair-back pivoted to each of said side members, an apron also pivoted to each of said side members, a longitudinally-movable seat-support intermediate said chair-back and said apron and pivoted to both, the pivotal points for the connection of said support to said chair-back being both while said chair-back is vertical and after same is partly inclined to the rear of the pivotal connection of said chair-back to each of said side members, and the pivotal points between 55 said seat-support and said apron being well to the rear of the points of pivotal connection of said apron to said side members.

3. In a barber's chair, the combination of 60 a chair-body comprising a pair of side-mem-

bers and means cross-connecting same, a chair-back pivotally connected to each of said side-members, an apron also pivoted to said side-members, and a longitudinally-movable seat-support provided at its front with a pair of forked upward projections and 70 at its rear with another pair of forked upward projections, said apron being provided with elongated rearwardly-extending arms pivoted within said forward forks and said chair-back having projecting means pivoted 75 in said rear forks.

4. The combination of side-members having a boss projecting from each and a projection from each side-member adjacent said boss so as to form a recess therebetween 80 and a rear rail the ends of which fit into said recesses.

5. The combination of side-members having a boss projecting from each and a projection from each side-member adjacent said boss so as to form a recess therebetween, a rear rail the ends of which fit into said recesses, and means for attaching said rail to 85 said bosses.

6. The combination of side-members having a boss projecting from each and a projection from each side-member adjacent said boss so as to form a recess therebetween, a rear rail the ends of which fit into said recesses, and lugs projecting from said rear rail 95 for attachment to said bosses.

7. The combination of side-members having a boss projecting from each and a projection from each side-member adjacent said boss so as to form a recess therebetween and a rear rail the ends of which fit into said recesses, and said rear rail being provided with lugs which extend substantially at right angles to said bosses for attachment thereto.

8. The combination of side-members having a boss projecting from each and a projection from each side-member adjacent said boss so as to form a recess therebetween and a rear rail the ends of which fit into said recesses, and said rear rail being provided with lugs which overlap said bosses for attachment thereto.

9. The combination of side-members having a boss projecting from each and a projection from each side-member adjacent said boss so as to form a recess therebetween and a rear rail the ends of which fit into said recesses, said rear rail being provided with perforated bosses, the perforations therein being adapted to receive bolts for the union of 120 said lugs with said bosses.

10. The combination of side-members having a boss projecting from each and a projection from each side-member adjacent said boss so as to form a recess therebetween and a rear rail the ends of which fit into said recesses, said bosses containing threaded recesses and said rear rail being provided with

perforated lugs, the perforations in which register with said threaded recesses, and bolts for connecting said lugs to said bosses.

11. In a barbers' chair, the combination of a chair-body comprising a pair of side-members, a chair-back pivoted to each of said side-members, an apron also pivoted to each of said side-members, a longitudinally-movable seat-support intermediate said chair-back and said apron and pivoted to both, the pivotal points for the connection of said support to said chair-back being, when said back is vertical, to the rear of the pivotal connection of said chair-back to each of said side-members, and the pivotal points between said seat-support and said apron being to the rear of and beneath the points of pivotal connection of said apron to said side-members.

12. In a barber's chair, the combination of a chair-body comprising a pair of side-members, a chair-back pivoted to each of said side-members, an apron also pivoted to each of said side-members, a longitudinally-movable seat-support intermediate said chair-back and said apron and pivoted to both, the pivotal points for the connection of said support to said chair-back being, when said back is vertical, to the rear of the pivotal connection of said chair-back to each of said side-members, and the pivotal points between said seat-support and said apron being to the rear of lines extending from the bottom of the apron to the points of pivotal connection of said apron to said side-members.

13. In a barber's chair the combination of concaved metal side-members having bosses projecting therefrom within said concavity, said bosses being formed with sockets therein, a chair-back having members projecting from the lower portion thereof, each of said members being provided with a pin extending therefrom and into one of said sockets, an apron provided in its upper portion with a pair of pins extending therefrom and into others of said sockets, and an intermediate seat support pivoted to said chair-back and said apron, the pivotal points for the connection of said support to said chair-back being, when said back is vertical, to the rear of the pivotal connection of said chair-back to each of said side-members, and the pivotal points between said seat support and said apron being to the rear of and beneath the points of pivotal connection of said apron to said side-members.

14. In a barber's chair, the combination of concaved metal side-members having bosses projecting therefrom within said concavity, said bosses being formed with sockets therein, a chair-back having members projecting from the lower portion thereof, each of said members being provided with a pin extending therefrom and into one of said sockets, an

apron provided in its upper portion with a pair of pins extending therefrom and into others of said sockets, and an intermediate seat support pivoted to said chair-back and said apron, the pivotal points for the connection of said support to said apron being to the rear of the points of pivotal connection of said apron to said side-members.

15. In a barber's chair, the combination of a pair of concaved side-members having socketed bosses projecting therefrom, a chair-back and an apron each having projections therefrom which seat in said sockets, a longitudinally-moving seat-support in pivotal connection with said apron and said chair-back, the weight of the chair-occupant being supported by the projections within said sockets, a piston to support said side-members, and a locking means extending from said piston to the apron of the chair.

16. In a barber's chair, the combination of a chair body comprising a pair of side-members, a chair-back pivoted to each of said side-members, an apron also pivoted to each of said side-members, a longitudinally-movable seat-support intermediate said chair-back and said apron and pivoted to both, the pivotal points of connection of said support to said chair-back being, when said back is vertical, to the rear of the pivotal connection of said chair-back to each of said side-members, a piston supporting said side-members, and locking means extending from said piston to the apron of said chair.

17. In a barber's chair, the combination of a pair of side-members having socketed bosses projecting therefrom, a chair-back pivoted to each of said side-members by members projecting from said back into said socketed bosses, an apron also pivoted to each of said side-members, a longitudinally-movable seat-support intermediate said chair-back and said apron and pivoted to both, a piston to support said side members, and a locking means extending from said piston to the apron of the chair.

18. In a barber's chair, the combination of a pair of side-members having socketed bosses projecting therefrom, chair-back pivoted to each of said side-members by members projecting from said back into said socketed bosses, an apron also pivoted to each of said side-members, a longitudinally-movable seat-support intermediate said chair-back and said apron and pivoted to both, a piston to support said side-members, and a rod slidable with respect to said piston and connected to said piston and to one of the movable parts of the chair, thereby to lock the chair.

19. In a barber's chair, the combination of a pair of side-members, a chair-seat supported thereby, a lug projecting inwardly from each of said side-members, a transverse

member which bears a pair of arms each spaced away a relatively short distance from an end of said transverse member, and means which bind said arms and lugs together, the ends of said transverse member engaging both said lugs and said side-members.

In testimony whereof I have affixed my signature in presence of two witnesses.

ERNEST E. KOKEN.
